Primary Examiner — Ania Aman(74) Attorney, Agent, or Firm — Clark Hill PLC; James R. Foley(57) CLAIM

The ornamental design of a suspension engine, as shown and described.

DESCRIPTION

FIG. 1 is a back view of the suspension engine;

FIG. 2 is a bottom view thereof;

FIG. 3 is a front view thereof;

FIG. 4 is a left side view thereof;

FIG. 5 is a perspective view thereof;

FIG. 6 is right side view thereof; and,

FIG. 7 is a top view thereof.

In the drawings, the broken lines depict unclaimed subject matter only and form no part of the claimed design.
